UNITED STATES PATENT OFFICE.

JOHN T. LISTER, OF CLEVELAND, OHIO.

SIGNALING APPARATUS.

1,258,791.

Specification of Letters Patent. Patented Mar. 12, 1918.

Application filed May 8, 1916. Serial No. 96,121.

To all whom it may concern:

Be it known that I, JOHN T. LISTER, a citizen of the United States, residing at Cleveland, in the county of Cuyahoga and 5 State of Ohio, have invented a certain new and useful Improvement in Signaling Apparatus, of which the following is a full, clear, and exact description.

This invention relates to an apparatus 10 adapted to be used on a moving railroad train or similar transportation medium for the purpose of functioning as a signaling device at the front and rear of the train in such a manner as to warn approaching 15 trains of the presence of the train carrying the apparatus.

Reference should be had to the accompanying drawings forming a part of this specification, in which Figure 1 is a view 20 more or less diagrammatic showing in elevation a train of cars with the apparatus mounted thereon. Fig. 2 is an elevation of one of the signaling devices.

At the present time it is customary in 25 operating railroad trains for the rear car to carry a light. This is usually a lantern which has a bull's-eye lens and the quantity of light emitted from the lantern is comparatively speaking small, so that unless the 30 atmosphere is very clear the light can not be seen but for a comparatively short distance behind the train.

If, for any reason, a train is stopped, it is customary for the brakeman to run back 35 on the track for a prescribed distance with a lantern with which he may signal an approaching train. This, however, involves the faithfulness of the brakeman and there is usually no check upon him nor any way 40 of absolutely ascertaining that he station himself with his lantern at a sufficient distance behind the train so as to insure the proper and timely signaling of an approaching train. The numbers of collisions which 45 have happened despite these precautions bear evidence of this fact.

At the front of the train it is not customary to have any signaling light, although of course the headlight of the engine will 50 in a measure fulfil this function.

However, none of the lights employed are sufficiently strong to penetrate fog for any great distance or to be visible any extended distance from the train when atmospheric 55 conditions are such as to tend to obscure extended vision.

Furthermore, the lanterns used upon the rear of a train are similar to other lights that are used upon signal towers and in similar positions, so that there is nothing 60 distinctive about the light which is carried upon the rear end of the train.

The fundamental idea involved in this invention is to place a high powered light upon the front and the rear car forming a 65 train. These lights are mounted so that they may be moved. The lights are operatively connected in a suitable manner by some means which when operated will cause a movement of both the front and the rear 70 lights. This movement will cause the beams of light from the sources of light to move and travel over a very wide area. In the present instance the lights at the end of the train are made to move in a path which is 75 the arc of a circle and preferably in vertical direction so that the beams of light will be projected normally straight forward, and when moved will be swung up so as to project the beams of light toward the sky. 80

In operating the lights they are continuously moved so that the beams of light from the sources of illumination will be continually moving up and down. This movement of the light beams will be visible for a great 85 distance both from the front and rear of the train and will attract the attention of trainmen upon trains which may be approaching the train from which the signal was operated. 90

Referring to the drawing, 1 and 2 will represent respectively the rear and front cars of a train. At 3 and 4 there is generally represented sources of illumination. 5 represents a cord or cable which is attached 95 to the sources of illumination for the purpose of moving them. This cord running through the cars in the same manner as the cable for operating the air signals upon trains, as at present employed. 100

It will be obvious that as the cable 5 is pulled downwardly the sources of illumination 3 and 4 will be turned about their pivots as indicated in dotted lines in Fig. 1, and when the cable 5 is released the sources of 105 illumination will return to their normal position.

In Fig. 2 I have shown in a little more detail one of the sources of illumination. This might comprise a casing 6 which would 110 contain a high powered light. The casing 6 will be suitably pivoted upon a standard

7 fastened upon the top of the car. The casing 6 will be provided with a stop 6^a which, when engaging with the standard 7 holds the casing 6 in horizontal position, the casing being held in such position by a spring 9.

From the casing 6 there extends an arm 8 which is secured to the cable 5.

This last description is but suggestive and 10 shows merely one form of carrying into effect my invention.

Having thus described my invention, what I claim is:

1. A signaling apparatus for use upon 15 railroad trains comprising a source of illumination upon the rear car of the train and a source of illumination upon the front car of the train, said sources of illumination being movably mounted, and means for simultaneously moving the sources of illumination.

2. A signaling apparatus for use upon railroad trains comprising a source of illumination mounted upon the first and the last 25 car forming the train, each of said sources

of illumination being mounted so that the direction of the beams of light emanating therefrom may be changed, and means whereby the said sources of illumination may be moved from within the train. 30

3. A signaling apparatus for use upon railroad trains comprising a high-powered source of illumination mounted upon the front car and the rear car of a train, said sources of illumination being movably mounted, and means whereby said sources of illumination may be moved to change the direction of the beams of light emanating from said sources of illumination. 35

4. A signaling apparatus for use upon 40 railroad trains comprising a source of illumination upon the front and rear car of a train each of said sources of illumination being pivotally mounted, and means whereby the said sources of illumination may be 45 moved about their pivots.

In testimony whereof, I hereunto affix my signature.

JOHN T. LISTER.
